UNITED STATES PATENT OFFICE

131,490

DESIGN FOR EMBOSSED PAPER OR THE LIKE

Kenneth C. Hamilton, Milwaukee, Wis., assignor to Milwaukee Lace Paper Company, Milwaukee,
Wis., a corporation of Wisconsin

Application July 14, 1941, Serial No. 102,124

Term of patent 14 years

To all whom it may concern:

Be it known that I, Kenneth C. Hamilton, a citizen of the United States, residing at Milwaukee, in the county of Milwaukee and State of Wisconsin, have invented a new, original, and ornamental Design for Embossed Paper or the like, of which the following is a specification, reference being had to the accompanying drawing, forming a part thereof.

In the accompanying drawing:

Fig. 2 is a similar view on a magnified scale.

I claim:

The ornamental design for embossed paper or the like, substantially as shown.

KENNETH C. HAMILTON.
